ATTORNEY

UNITED STATES PATENT OFFICE.

ANDREW JOHNSON, OF HASKELL, NEW JERSEY.

PROJECTILE.

1,311,521.

Specification of Letters Patent. Patented July 29, 1919.

Application filed December 7, 1917. Serial No. 206,066.

To all whom it may concern:

Be it known that I, ANDREW JOHNSON, a citizen of the United States, residing at Haskell, in the county of Passaic and State of New Jersey, have invented certain new and useful Improvements in Projectiles, of which the following is a specification.

This invention relates to projectiles, and more particularly to an explosive shell of the incendiary type.

One of the main objects of the invention is to provide a shell of the character stated of simple construction and operation which may be readily produced at comparatively small cost. A further object is to provide a shell which is capable of containing a comparatively large amount of highly inflammable fluid which will be ignited when the shell explodes so as to set fire to objects adjacent the target struck. Another object is to provide a shell in which the elements are so related as to permit the shell to be quickly and easily assembled. A still further object is to provide a shell which, in the event that it is not exploded by contact with a target, will nevertheless be exploded by means of a fuse ignited at the time that the projectile is fired from a gun. Further objects will appear from the detailed description.

In the drawings:

Figure 1 is a side view of a shell constructed in accordance with my invention.

Fig. 2 is a central longitudinal section through the shell.

Fig. 3 is a view similar to Fig. 1 showing the shell as having been shot from a gun and traveling toward the target.

The shell is of usual shape having the cylindrical body portion 1, the tapered nose 2 and the base 3. This shell may be formed by casting in the usual manner from suitable material, preferably steel so tempered as to be easily frangible so as to be readily shattered into small fragments by the force of the explosion. The nose 2 of this shell is provided with an axial bore 4 which is in axial alignment with an inwardly directed threaded nipple 5 provided at the center of base 3. This nipple receives the outer end of a cylindrical explosive casing 6, the outer end portion of which is exteriorly threaded and secured in nipple 5 as at 7. This casing is provided, at its forward end, with an integral reduced neck 8 disposed axially of casing 6, this neck fitting snugly into the bore 4 of nose 2. Casing 6 has its outer end

closed by a hollow screw plug 9 threaded into the same, this casing and the neck 8 thereof being adapted to contain the explosive charge 10. A cartridge 11 fits snugly in the outer end portion of neck 8 so as to be secured tightly therein frictionally. This cartridge is open at its inner end so as to communicate directly with the neck 8, and is provided in its outer end with a percussion cap 12. This cap is adapted to be engaged by a firing pin 13 projecting inwardly from a firing head 14 frictionally secured in the outer end of bore 4.

The hollow screw plug 9 is provided with a central outwardly directed nipple 15. This nipple provides a post about which may be wrapped a time fuse 16, this fuse being passed through the nipple so that a portion 17 thereof is positioned within the casing 6 so as to ignite the explosive charge 10 when the fuse is used. The coils of this fuse are held frictionally within the plug 9 between the inner face thereof and the post 15. The space between the inner surface of the wall of the shell and the casing 6 constitutes a reservoir 18. This reservoir is filled with a highly inflammable liquid such as gasoline, or any other suitable liquid which will be readily ignited from the explosion of the shell and will generate intense heat when burning.

In assembling the shell, the bore 4 will be closed by a plug or stopper inserted into the same, after which the proper amount of liquid will be poured into the shell through nipple 5, the amount of liquid for a shell of the given caliber being readily ascertained by experiment. After this has been done, the casing 6 is inserted, the neck 8 thereof fitting snugly into bore 4, the casing being secured in position by being threaded into nipple 5. The explosive charge may then be placed in the casing, and the plug 9 carrying the fuse 16 threaded into the rearward end thereof. The shell may now be stood upon its base, and the cartridge 11 inserted into neck 8, after which the firing head 14 may be secured in bore 4 of the nose. This shell may be shot from a gun or mortar in the usual manner. Normally, the impact of the shell with the target will be sufficient to drive the head 14 inwardly so as to detonate the percussion cap 12 thus firing the cartridge 11 which acts to ignite the explosive charge thus exploding the shell. This explosion will first shatter the inner

casing 6 so as to ignite the liquid contained within the shell, the body of the shell being shattered practically simultaneously with the explosion of the explosive charge, and 5 the ignition of the liquid, the flaming liquid being thus spread over a comparatively great area by the force of the explosion so as to ignite objects in the neighborhood of the target struck. The fuse 16 will be 10 ignited when the shell is fired from a gun. In the event that the object aimed at is not struck, the fuse will act to ignite the explosive charge in casing 6 thus insuring explosion of the shell. This fuse may be made 15 in suitable lengths, being graduated or marked so that the length of the fuse may be regulated in accordance with the distance of the target away from the gun, to insure explosion of the shell at the instant it reaches 20 the target, or very nearly so.

It will be seen that I have provided a projectile of very simple construction and operation which may be manufactured at low cost, the various elements of which are 25 so related as to be quickly and easily assembled, the body of the shell constituting a reservoir which is adapted to contain a comparatively large amount of a highly inflammable liquid which will be ignited when 30 the shell is exploded and scattered, by the force of the explosion over a comparatively great area.

What I claim is:

1. In a projectile, a body having a charge-containing chamber, a closure therefor, said closure having a receiving space, a nipple extending thereto, and a fuse in said space wrapped around the nipple, and said fuse extending into the chamber.
2. In a projectile, a hollow body having an axial bore at the nose and an axial bore at the base, a charge-containing casing bridging said bores and disposed in the bore of the base, said casing having a reduced 45 portion disposed in the bore of the nose, said reduced portion serving to provide in effect a fuse for the remainder of the charge of the casing and provide a shoulder at the junction of the reduced portion with the remainder of the casing to serve as an abutment for the charge after firing to aid in shattering the casing and detonating means at the nose of the body coöperating with the fuse charge in the reduced portion of 50 the casing.
3. In a projectile, a hollow body having

an axial bore in its nose and an axial bore in its base, a detonating member in the bore of said nose, a charge-containing casing insertible through the bore of the base, and 60 into the bore of the nose, firing means carried by the casing to coöperate with the detonating member, and means between the casing and the body to permit adjustment of the casing to position the firing means relative to the detonating member during 65 assembly of the projectile.

4. In a projectile, a hollow body provided with an axial bore at the nose, and with an axial bore at the base, an inwardly extending flange at the bore of the base provided with interior screw threads, the bore of the nose having a substantially smooth wall throughout its length, a charge-containing casing having a reduced portion, the charge 75 in said portion in effect forming a fuse for the remainder of the charge of the casing, a firing member disposed in said reduced portion, said reduced portion at the junction with the remainder of the casing forming a 80 shoulder for abutment with the gases after firing of the charge to assist in shattering the casing, said casing being insertible through the bore of the base with the reduced portion entering and closing the bore 85 of the nose, said body adapted to contain a liquid to coöperate with the charge and to be placed in the body before insertion of the casing, the bore of the nose permitting insertion of a temporary stopper during the 90 filling of the body, a detonating member in the nose in advance of the reduced portion, said casing having screw threads to coöperate with the screw threads of the base to permit adjustment of the casing to position 95 its firing means relatively to the detonating member during assembly, said casing adjacent the base having interior screw threads, a plug having interior screw threads engaging interior screw threads of the casing, 100 said base having an outwardly extending nipple, a fuse extending through the nipple and said fuse being wrapped around the nipple and occupying the surrounding space in the plug.

In testimony whereof I affix my signature in presence of two witnesses.

ANDREW JOHNSON.
